ROOF AND FLOOR CONSTRUCTION

Edward Clyde Hoge, Cincinnati, Ohio, assignor to
 Lathrop-Hoge Gypsum Construction Company,
 Cincinnati, Ohio, a partnership composed of
 Jay C. Lathrop and Edward Clyde Hoge

Application November 4, 1937, Serial No. 172,830

7 Claims. (Cl. 72—71)

My invention relates to the construction of roofs and floors for buildings of a monolithic character.

Modern construction and design call for roof and floor constructions which are more and more resistant to heat loss, but which, at the same time, may be constructed relatively inexpensively. This has become quite a problem in monolithic buildings, wherein inflammable materials due to fire hazards must be greatly minimized, and where the building must be pleasing of appearance as well as permanent.

It is an object of my invention to provide a roof or floor construction which has a decidedly high insulating value, and which, at the same time, is fireproof, vermin-proof, and permanent.

These and other objects of my invention, which will be set forth hereinafter, or will be apparent to one skilled in the art upon reading these specifications, I accomplish by that certain construction and arrangement of parts, of which I shall now describe a preferred embodiment. Reference is now made to the drawing, which forms a part hereof and in which—

Figure 1 is a cross section of a floor or a roof embodying my invention.

Figure 2 is a section taken on the section line 2—2 of Figure 1.

Figure 3 is a section of a modification of my invention.

There is a system of floor and roof construction known as the Hoge system, which has been in vogue for many years, and which is described in my patent issued August 14, 1923, bearing No. 1,464,711. In this construction, a series of bars or rails are laid in interspaced relation with composition board on the extending flanges of the rails in order to form a complete surface. Reinforcing material is then laid across the tops of the rails, permitting a sag between the rail tops, and slab material such as gypsum is poured over the whole to fill in the spaces between the rails and to cover the reinforcing material. This construction, while being highly beneficial, does not have the insulation value necessary in modern construction, in that the metal of the rails being a relatively good conductor, in cold weather is apt to become quite cold due to the fact that the rail tops are relatively close to the surface. This, of course, in some cases tends to condense moisture on the bottom part or underside of the flanges when the temperature of the room is relatively high and humid. It has also been my observation that the composition board of the under surface, is not as highly insulating as

at present desired, and if the composition boards resting upon the flanges are formed of insulation material in order to increase the insulation of the floor as a whole, the moisture from the slab when it is poured, has a tendency to permeate the insulation board and discolor it.

Briefly, in the practice of my invention, I provide interspaced bars 1, having base flanges 2. Resting on these base flanges and forming a permanent under surface, I provide composition boards 3. These composition boards may be the well-known plaster board, or may be boards having sound-absorbent and/or heat insulating qualities such as the fibrous air-celled boards, similar to Celotex and well known in the industry. In this construction, my composition boards straddle the projecting flanges 2 of adjacent rails, and I find it desirable, but not necessary, to place a strip or a T-strip 4 between the adjacent and abutting edges of the succeeding boards 3, in order to give a pleasing paneled appearance from below.

Resting on the composition boards 3 and between the upstanding web 5 of the bars, I place moisture-resistant insulating pads 6, composed of mineral fiber or the like. There is a silica fiber and a moisture-proof rock fiber, both of which I have found quite satisfactory. I do not intend, however, to limit myself to the specific insulating material, since any highly insulating material such as mineral wool made from rock, slag, glass, or similar material, and which will fill the space between the under surface board 2 and the top level of the bars 1, or even thicker if desirable, answer my purpose. It is a very important feature of my invention that this space be completely filled with the pads or batting of insulating material completely to the top edge of the bars or beyond. The fact that this space is completely filled will cut down any substantial air space which would further the breathing of the structure through the cracks, where the boards 3 abut or where the board edges lie on the flanges 2 of the bars. Thus, condensation within the structure will not readily take place.

Metal reinforcing material 7 is laid transversely over the bars 5 and the top slab 8 is poured so that the reinforcing material 7 will be contained therein. This top slab may be formed of gypsum, plaster, or any one of the lighter concretes, such as the ones which contain exfoliated vermiculite, or any of the gaseous lighter concretes. I do not intend to limit myself necessarily to the material of the slab 8 or to a single poured slab, since I have found it satisfactory to use a pre-

formed slab with a minimum size which will permit the straddling of two adjacent rails. It is, however, necessary that this slab 8, whether of pre-cast slabs, or of a single poured slab, must contain reinforcing material extending transversely of the cross bar, so as to strengthen the same.

10 The above structure is such that some moisture may get down into the mineral fiber insulating pads or batting 6, but there is no weight resting and exerting a pressure on this insulating material 6, in order to consolidate it and ruin its beneficial features, and as noted, there will be a minimum of breathing space to set up moisture condensation.

In this construction, the entire structural slab is over and above the rails 1, and the rails are thereby thoroughly insulated from the outside temperature, which prevents them from conducting temperature differentiations through the structure. Due to this construction, the total load of the slab 3 and the reinforcing material 7 is carried directly on the bars 1, so there is no pressing upon and consolidating of the insulating material 6.

25 The above described construction forms a roof or a floor which is completely fire and vermin-proof, and which has a high degree of resistance to heat loss, as well as permanency of construction and relative cheapness. I do not necessarily have to use cross bars in the form of a rail, or a T, since it is possible to use H-sections. However, it is necessary that my bars have base flanges as is clearly apparent.

35 When pouring certain material for my slab 8, it may be beneficial to place a layer of felted paper or composition board 9 on top of the insulating material 6 and the rails, so that when the material of the slab is poured, it will bind 40 to the felted paper or composition board. It may also be beneficial to water-proof either this layer and/or the under surface boards 3 by saturation or coating with some material well known in the art and the above is understood 45 to be included in the contemplation of my invention.

It is to be understood that different forms of my preferred form may be made without departing from the spirit of my invention.

50 Having thus described my invention, what I claim as new and desire to secure by Letters Patent is:

1. A roof or floor structure for buildings comprising metal cross bars having base flanges laid in interspaced relation, composition boards supported on the flanges of the cross bars to form a permanent under surface, insulating material completely filling the spaces between the cross bars and supported by said under surface, a metal reinforcement extending transversely of the cross bars and located above the same, and a consolidated body extending above and supported on the cross bars and containing the metal reinforcement, for the purpose described.

35 2. A roof or floor structure for buildings comprising metal cross bars having base flanges laid in interspaced relation, composition boards supported on the flanges of the cross bars to form a permanent under surface, insulating material 10 completely filling the spaces between the cross bars and supported by said under surface, a metal reinforcement extending transversely of

the cross bars and located above the same, and a consolidated body extending above and supported on the cross bars and containing the metal reinforcement, said consolidated body comprising gypsum plaster, for the purpose described. 5

3. A roof or floor structure for buildings comprising metal cross bars having base flanges laid in interspaced relation, composition boards supported on the flanges of the cross bars to form a permanent under surface, insulating material completely filling the spaces between the cross bars and supported by said under surface, a metal reinforcement extending transversely of the cross bars and located above the same, and a consolidated body extending above and supported on the cross bars and containing the metal reinforcement, said consolidated body comprising light concrete, for the purpose described.

4. A roof or floor structure for buildings comprising metal cross bars having base flanges laid in interspaced relation, composition boards supported on the flanges of the cross bars to form a permanent under surface, insulating material completely filling the spaces between the cross bars and supported by said under surface, a metal reinforcement extending transversely of the cross bars and located above the same, and a poured unitary slab extending above and supported on the cross bars and containing the metal reinforcement, for the purpose described. 20 25 30

5. A roof or floor structure for buildings comprising metal cross bars having base flanges laid in interspaced relation, composition boards supported on the flanges of the cross bars to form 35 a permanent under surface, insulating material completely filling the spaces between the cross bars and supported by said under surface, a metal reinforcement extending transversely of the cross bars and located above the same, and a poured 40 unitary slab extending above and supported on the cross bars and containing the metal reinforcement, said slab consisting of gypsum plaster, for the purpose described.

6. A roof or floor structure for buildings comprising metal cross bars having base flanges laid in interspaced relation, composition boards supported on the flanges of the cross bars to form a permanent under surface, insulating material completely filling the spaces between the cross bars and supported by said under surface, a metal reinforcement extending transversely of the cross bars and located above the same, and a poured unitary slab extending above and supported on the cross bars and containing the metal reinforcement, said slab consisting of light concrete, for the purpose described. 45 50 55

7. A roof or floor structure for buildings comprising metal cross bars having base flanges laid in interspaced relation, composition boards supported on the flanges of the cross bars to form a permanent under surface, insulating material completely filling the spaces between the cross bars and supported by said under surface, a layer of felted paper positioned over and covering said insulating material, a metal reinforcement extending transversely of the cross bars and located above the same, and a consolidated body extending above and supported on the cross bars and containing the metal reinforcement, for the purpose described. 60
